(57) **CLAIM**

The ornamental design for a disposable arm cast cover, as shown and described.

DESCRIPTION

FIG. 1 is a front perspective view of a disposable arm cast cover showing my new design;
 FIG. 2 is a side elevational view thereof, the opposite side view comprising a mirror image;
 FIG. 3 is a top plan view thereof;
 FIG. 4 is a front elevational view thereof; and,
 FIG. 5 is a rear elevational view thereof.
